UNITED STATES PATENT OFFICE.

CHARLES A. BICKETT, OF CINCINNATI, OHIO.

MOISTURE-PROOF PAPER-STOCK AND METHOD OF PRODUCING.

1,203,303.

Specification of Letters Patent.

Patented Oct. 31, 1916.

Application filed April 1, 1915. Serial No. 18,588.

To all whom it may concern:

Be it known that I, CHARLES A. BICKETT, a citizen of the United States, residing at Cincinnati, in the county of Hamilton and State of Ohio, have invented certain new and useful Improvements in Moisture-Proof Paper-Stock and Methods of Producing, of which the following is a specification.

My invention relates to improvements in water or moisture proof paper stock and method of producing the same.

One of its objects is to provide a paper stock which is water or moisture proof and which is adapted to receive printing on one side.

Another object is to provide a stock which may be produced from either heavy strong paper stock or light thin paper stock moisture proofed on one side.

Another object is to provide an improved method of producing stock from a single sheet of material so that all or any desired portion of one surface may be coated with moisture proof material while the other face will be free from injury to its appearance or printing properties from the application of the moisture proof material.

Another object is to prevent the moisture proofing material penetrating deeply into or through the texture, of the paper stock, thereby securing a thin but dense and impervious coating of moisture proof material.

Another object is to provide for applying the moisture proofing material to certain portions only of one face of the stock, leaving other portions of the same face free to receive adhesive material or to be acted upon by adhesive material in setting up paper containers.

My invention also comprises certain details of form, combination and arrangement, and order of procedure, all of which will be fully set forth in the description of the accompanying drawings, in which:

Figure 1 is a diagram illustrating the mechanism and method of coating or applying moisture proof material to a sheet of paper stock. Fig. 2 is an enlarged sectional detail through my improved stock. Fig. 3 is an inside plan view of a blank for a paper container, and illustrating one of the applications of my invention.

My invention is designed to produce a paper stock for the manufacture of paper containers such as paper sacks, envelops, pouches and boxes in which the stock is moisture proof on one face while the oppo-

site face is unaffected by moisture proof material and is free to receive printing, writing or adhesive materials. It is also designed to provide paper stock to which the moisture proofing material is applied locally to portions only of one face of the stock leaving other portions uncoated to provide laps or joints to be united by adhesive material.

The moisture proofing material most suitable and the one preferably employed is paraffin, although others may be employed if desired. In order to apply the moisture proofing material to one face of the sheet and prevent it from penetrating through to the opposite face of the sheet, or to prevent it from penetrating too deeply into the fiber of the sheet I apply the heated or fluid paraffin to one face of the sheet and substantially at the same time apply a liquid to the opposite face of the sheet which is immiscible with the paraffin, and which penetrates from one side into the body of the sheet at substantially the same time that the paraffin penetrates into the sheet from the opposite side. Thus the two materials as they penetrate into the body of the sheet, being immiscible one with the other, each constitutes a barrier, where they meet in the body of the sheet, to the further penetration of the other. Water will serve and is preferably employed as the liquid to be applied to the opposite face of the sheet. The water is preferably heated so as not to have too great a chilling effect upon the paraffin, but the temperature of the water may be varied depending upon the weather and other conditions. After the two substances have met in the interior of the sheet and have respectively barred the penetrating progress of the other, the paraffin commences to cool and assumes a solid or semi-solid condition while the water quickly vaporizes and disappears leaving the paper stock coated with moisture proof material upon one side only.

In Fig. 1, I have illustrated one form of apparatus to carry out the process and produce my improved paper stock. A represents a sheet or roll of paper to be treated. B represents a bath containing moisture proofing material preferably paraffin having a heating jacket 2 and pipes 3 and 4 to conduct steam hot water or other heating medium to and from the jacket 2. C represents a bath containing some liquid immiscible with the moisture proofing material, preferably water or a sizing. 5 represents

a jacket by means of which the bath C may be maintained at the desired temperature, and 6 and 7 pipes to conduct a heating medium or if desired a cooling medium to and from the jacket 5.

6 A roller D dips into the bath B and in turn distributes moisture proofing material from the bath to a roller E in contact with one face of the sheet A. The roll E may 10 have a plain or continuous cylindrical face to coat the entire face of the sheet, or it may have recesses 8 in its face so as to leave an uncoated margin along one edge of the sheet, or an uncoated pattern along or across the sheet so that the sheet may be subsequently blanked into box or pouch blanks.

10 A roller F dips into the bath C and distributes the contents thereof to the face of a roller H which preferably contacts with 20 the opposite face of the sheet at a point substantially opposite the roller E and thus the two materials proceed to penetrate into the body of the sheet from opposite sides at substantially the same time and continue to 25 penetrate until they meet at some point in the interior of the sheet, where each prevents further penetration on the part of the other. By various means the penetration of moisture proof material may be controlled to secure a heavy or light coating thereof, as for 30 instance, by regulating the amount of the respective materials applied to opposite sides of the sheet, or by applying one material slightly in advance of the other, or by applying 35 a size in place of pure water. In practice the moisture proof material instead of penetrating to the opposite face of the sheet and forming a more or less open or porous coating is concentrated into a thinner but 40 dense and impervious coating, and results in a material saving in moisture proof material while securing a more moisture proof product.

45 After the two materials have been applied to opposite sides of the sheet, the sheet is fed forward a considerable distance to a receiving roll K on which it is wound. The distance between the rolls E H and roll K should be relatively greater than shown in 50 Fig. 1 and sufficient to enable the sheet to cool sufficiently for the moisture proof material to practically solidify, and during this period the water is practically all evaporated out of the sheet. For removing the 55 water a drying chamber 17 with air current supply 18 may be employed through which the sheet is fed in its passage from rolls E H to roll K.

60 In Fig. 2 A' represents a section of the sheet in enlarged cross section showing the moisture proof material 12 as having penetrated practically half way through the sheet where it has been stopped by the penetration of water or similar immiscible material from the opposite face.

In Fig. 3 is illustrated in plan a blank for a moisture proof envelop or pouch, the main portion 14 of one face being coated with moisture proof material, leaving uncoated laps 15 and 16 to receive adhesive material. 70 To produce blanks of this and similar character the roller E is provided with longitudinal or transverse grooves 8 where the uncoated portions are desired, and each revolution of the roller coats a portion of the 75 sheet sufficient for one or more blanks. The sheet is subsequently fed to dies which cut out the blanks and score them for folding. Tubes for producing sacks and like articles may be formed by leaving a continuous uncoated margin along one edge of the sheet, which may be subsequently employed as a 80 glue lap to form the sheet into a tube.

85 My invention as herein illustrated and described is capable of considerable modification without departing from the principle or spirit thereof.

Having described my invention, what I claim is:

1. A paper stock for paper containers 90 comprising a plane-faced sheet of paper one of the faces of which is coated with paraffin which does not penetrate to the opposite face, said opposite face, being in its original condition to receive printing or adhesive 95 material.

2. A paper stock for paper containers comprising a plane-faced sheet of paper one face of which is coated with paraffin except where it is desired to apply an adhesive material to assemble the container, and in which the paraffin coating does not penetrate to the opposite face of the sheet, said opposite face being in its original condition to receive printing on adhesive material. 105

3. A stock for paper containers comprising a plane-faced sheet of paper coated on one face with paraffin or like moisture proof material which is limited in its penetration 110 to a fraction of the thickness of the sheet leaving the opposite face of the sheet in its original condition to receive printing or adhesive material.

4. A stock for paper containers comprising a plane-faced sheet of paper one face of which has certain portions coated with moisture proof material and other portions free to be acted upon by adhesive material, said moisture proof material being limited in its 115 penetration to a fraction of the thickness of the sheet leaving the opposite face of the sheet in its original condition to receive printing or adhesive material. 120

5. The method of preparing moisture 125 proof plane-faced paper stock for paper containers which comprises applying fluid moisture proof material to one face of a sheet of paper and at substantially the same time applying a fluid immiscible with said 130

moisture proof material to the opposite face of the sheet.

6. The method of preparing moisture proof plane-faced paper stock for paper containers which comprises applying fluid moisture proof material to one face of a sheet of paper, at substantially the same time applying a fluid immiscible with said moisture proof material to the opposite face 5 of the sheet, and subsequently drying the sheet at a temperature lower than the fusing temperature of the moisture proof material to leave the moisture proof coating thereon 10 undisturbed and to remove the fluid immiscible therewith.

7. The method of preparing a moisture proof paper stock which comprises applying moisture proof material to one face of a sheet of paper, at substantially the same 20 time applying a fluid immiscible with said moisture proof material to the opposite face of said sheet, and subsequently subjecting

the sheet to a drying operation at a temperature lower than the melting point of said moisture proof material.

8. The method of preparing a moisture proof paper stock which comprises applying a moisture proof material to certain portions of one face of a sheet of paper leaving other portions of the same face uncoated 25 with moisture proof material, at substantially the same time applying a fluid immiscible with said moisture proof material to the opposite face of said sheet, and subsequently subjecting the sheet to a drying 30 operation at a temperature lower than the melting point of said moisture proof material.

In testimony whereof I have affixed my signature in presence of two witnesses.

CHARLES A. BICKETT.
